UNITED STATES PATENT OFFICE.

SERN MADSEN, OF CLINTON, IOWA, ASSIGNOR TO CURTIS COMPANIES, INC., OF CLINTON, IOWA.

UNIVERSAL CARVING MACHINE.

Application filed November 4, 1925. Serial No. 66,735.

The object of my invention is to provide a universal carving machine adapted for use in woodworking establishments for cutting irregular or curved surfaces either in a horizontal plane or in a vertical plane or in a combination of both.

More particularly, it is my object to provide a machine of this type of relatively simple and inexpensive construction having 10 adjustments which can be quickly and easily made for cutting the more intricate shapes, such for example as bends, easings, goose-necks, and volutes encountered in stair construction.

Another object of my invention is to provide in a machine of the general class described a table supported for rotary swinging movement and for adjustment horizontally and vertically and to provide a motor 20 mounting having vertical and horizontal adjustment and rotary swinging movement, whereby cutters may be moved vertically and horizontally, and whereby a motor may be turned over for presentation to the work 25 of cutters operated from either end of the motor shaft.

With these and other objects in view, my invention consists in the construction, arrangement and combination of the various 30 parts of my universal carving machine, whereby the objects contemplated are attained, as hereinafter more fully set forth, pointed out in my claims, and illustrated in the accompanying drawings, in which:

Figure 1 is a top or plan view of a universal carving machine embodying my invention.

Figure 2 shows a front elevation of the machine, to-wit, an elevation from the operator's side of the device.

Figure 3 shows a side elevation of the machine, parts being broken away and parts being shown in section, the machine being viewed from the right side of the device as 45 shown in Figure 2.

Figure 4 is a detail, sectional view taken on the line 4—4 of Figure 2.

Figure 5 is a detail, sectional view taken on the line 5—5 of Figure 3.

Figure 6 is a detail, sectional view taken on the line 6—6 of Figure 2.

Figure 7 is a detail, sectional view taken on the line 7—7 of Figure 2.

Figure 8 is a sectional view taken on the line 8—8 of Figure 2.

Figure 9 is a similar view taken on the line 9—9 of Figure 2.

Figure 10 is a similar view taken on the line 10—10 of Figure 2.

Figure 11 is a detail, sectional view taken on the line 11—11 of Figure 2.

Figure 12 is a detail, sectional view of the cutter mounting taken on the line 12—12 of Figure 2.

Figure 13 is a similar view taken on the same line illustrating a slightly different cutter.

Figure 14 is a perspective view of one of the forms which may be carved with my 70 carving machine.

Figure 15 is a plan view of the same illustrating the arrangement of the grain in the wood for the purpose of bringing out certain advantages of my carving machine in connection with the explanation of its 75 operation.

Figure 16 is a section of the form being carved, showing the pattern arranged thereon in proper relation to the cutter.

Figure 17 shows the arrangement of the 80 cutter and form being carved at one stage in the operation.

Figures 18 and 19 are sectional views of the work table showing a jig thereon with work arranged in different positions on the 85 jig for different carving operations; and

Figure 20 is a section through a portion of one of the jigs and one of the gripping fingers mounted thereon.

It will be understood from the foregoing 90 that the general purpose of my invention is to provide a carving machine which can be used for performing a great variety of operations and for carving many different shapes.

For purposes of illustration, I have shown 95 in Figure 14 a finished carving, which illustrates the kind of work that may be done on a machine of this kind.

Generally speaking, the machine consists of a main frame mounted on legs. At one 100 side of this frame is a work supporting table, which is vertically adjustable and also ca-

pable of being revolved around a horizontal axis. A motor is mounted above the table for universal horizontal adjustment, for vertical adjustment, and for rotary swinging movement. In order to secure the proper mounting of the motor, there is mounted on the main frame, what may be called a carriage movable horizontally in one direction. On the carriage is mounted a base movable horizontally in directions at right angles to the movement of the carriage. Supported on this base is a column upon which is a vertically adjustable yoke. The yoke supports a beam or shaft for longitudinal adjustment and for rotation. At one end of the beam or shaft is a vertically, adjustable turret base in which is mounted for rotary movement a turret. The turret supports a motor, which is also mounted for slight adjustment in line parallel with its shaft. The motor has double-end shaft extensions for receiving respectively right and left-hand cutters, either one of which may be brought into cutting position for operating upon work on the table by revolving the turret.

I shall now describe my universal carving machine in greater detail.

In the drawings herewith, I have used the reference numeral 10 to indicate generally what I have called the main frame, which is supported on legs 11. The main frame may be a box-like structure.

For convenience, I will consider the side adjacent to which the workman stands during the operation of the machine to be the front of the machine. This is the side shown in elevation in Figure 2.

The main frame 10 supports the operating mechanism of the machine.

Work table.

The table for supporting the stock or work is mounted on the main frame in the following manner:

A large beam or shaft 12 extends across the frame from side to side and is journaled in the opposite sides thereof.

Removable collars 13 and 14, shown for instance in Figure 2, are held in place by set screws 15 and ordinarily prevent lengthwise movement of the beam or shaft 12 with relation to the main frame 10.

It will be observed, however, that upon loosening the set screws 15, the shaft 12 may be adjusted longitudinal with relation to the main frame for thus permitting of one adjustment of the work table, which is supported on the shaft 12.

This table, which I have indicated at 16 in Figures 1, 2 and 3, is supported adjustably on the shaft 12 in the manner now to be described and is rotatable with the shaft and is capable of being locked in certain positions by the means later herein referred to.

The beam or shaft 12 carries at its right-

hand end, as viewed in Figures 1, 2 and 7, a head 17, having the gibbed ways 18 (see Figure 7), in which is slidably mounted the vertical leg 16^a of the table 16.

The head 17 has a projecting ear 19 and the leg 16^a has a projecting ear 20, as shown in Figures 1 and 3.

A rod 21 has a screw-threaded connection with the ear 20. The rod 21 is provided with a shoulder 22 adjacent to the lower side 75 of the ear 20 and with a removable collar 23, just above the ear 20, for thus permitting rotation of the rod 21 in the ear 20 and preventing sliding movement of the rod.

On the lower end of the rod 21 is a hand-wheel 24. By rotating the rod 21, the table 16 may be adjusted radially with relation to the shaft or beam 12. Thus when the parts are in the position shown for example in Figures 1, 2 and 3, the rotation of the 85 shaft 21 will effect a vertical adjustment of the table 16.

The shaft 12, being rotatably mounted, the table may be swung around the extended axis of that shaft. A handle 25, shown for 90 instance in Figures 1 and 2, is provided for this purpose.

For limiting the rotary swinging movement of the table in one direction and holding it normally in position with its upper 95 surface horizontal, there is provided, as shown in Figure 3, a set screw 26 mounted in a lug 27 on the frame 10 and adapted to be locked in any suitable position by means of a lock nut 28.

The set screw bears against the lower part of the head 17 and is capable of slight adjustment.

Ordinarily when the handle 25 is thrown upwardly for swinging the table 16 and is then allowed to swing back, the head 17 engages the end of the set screw 26 when the table is returned to normal position. The table is thus swung around the extended axis of the beam or shaft 12 for bringing 110 the work on the table to position for being operated on by the cutter of the motor hereinafter described.

For releasably locking the table 16 against rocking movement in cooperation with the set screw 26, I provide the following means:

On the frame 10, spaced horizontally from the set screw 26 are vertically, spaced ears 28^a. A catch 28^b is pivoted between its ends between the ears 28^a by means of the 120 pivot pin 28^c. (See Figures 2 and 3.) One end of the catch 28^b normally stands in engagement with the head 17 at the opposite side thereof from the set screw 26.

A lever 28^d has its upper end standing between the other end of the catch 28^b and the frame 10, as shown in Figures 2 and 3, and is pivoted on the bracket 28^e on one of the legs 11, and has at its lower end the foot pedal 28^f. The ears 28^a are close enough to 130

the frame 10 to permit the head 17 to clear them.

The pivot point of the lever 28^d is so arranged that when the pedal 28^e is pushed downwardly and inwardly, the lever 28^d will actuate the catch 28^b to cause it to swing clear of the head 17 and permit the table to be swung with its rotary movement.

The spring 28^g interposed between the 10 catch 28^b and the frame 10 tends to yieldingly hold the catch in position for locking the head 17 against its rotary swinging movement, as shown in Figure 5.

When the operator desires to rotate the 15 head, he actuates the foot pedal 28^f and then by grasping the handle 25 can swing the head as he desires.

It is sometimes desirable to lock the table 16 in different positions of its rotary, swinging 20 movement and for that purpose, the following means are provided.

It may be noted in a preliminary way that the head 17 is fixed to the shaft or beam 12 and that the shaft or beam 12 rotates in its 25 bearings when the table 16 is swung around its horizontal axis of rotation.

For locking the shaft 12 in different positions of its rotary movement, I provide between the shaft 12 and the top portion of 30 the frame 10 immediately overhanging the shaft, as shown in Figure 4, a pair of sliding blocks 12^a forming gripping shoes. These blocks are arranged to fit the contour of the shaft 12 on opposite sides of the vertical 35 diametrical center line therethrough.

A control rod 12^b is extended through the frame 10 and rotatably through a left-hand block 12^a, as shown in Figure 4. It then has a screw-threaded connection with the 40 right-hand block 12^a, shown in Figure 4. On the rod 12^b is a shoulder 12^c bearing against the left-hand block 12^a.

It will be seen that by rotating the rod 12^b by means of the hand wheel 12^d thereon, the 45 blocks 12^a may be drawn toward each other or forced apart.

When drawn toward each other, they will serve as wedges for engaging the frame 10 and the shaft 12 for locking the shaft 12 against rotation.

Cutter support.

A carriage 29 is mounted on the base 10 for movement in a horizontal plane forwardly and rearwardly. This carriage is 50 shown in Figures 1, 3, 6 and 7. It comprises a substantially rectangular frame. In the upper part of the frame 10 are grooves 30 extending for-and-aft, and in the under surface of the carriage 29 are grooves 31, as shown for instance in Figure 1.

Between the base for the frame 10 and the carriage 29 are ball retainers 32 carrying the 55 balls 33, which travel in the grooves 30 and 31. (See Figures 1 and 7.)

It will thus be seen that the carriage 29 may be rolled fore-and-aft on the frame 10. The frame 10 has a central opening 34, shown particularly in Figure 7.

Secured to the inner edge of the rectangular frame forming the carriage 29 at a suitable distance from the front and rear thereof is a downwardly projecting plate 35 adapted to engage the frame 10 and to limit the fore-and-aft movement of the carriage 29 on the 75 frame 10. (See Figures 6 and 7.)

For moving the carriage 29 on the frame 10, a shaft 36 is supported in bearings 37, as shown in Figure 1 at the front of the frame 10. Mounted on the shaft 36 is a hand wheel 80 38 having a handle 39. Mounted on the frame 10 at the right side thereof near the rear of the frame is a stub shaft 40 on which is a sprocket 41 in line with a sprocket 42 on the shaft 36 as shown in Figure 3. 85

A chain 43 has its lower stretch extended below the shaft or beam 12, as shown in Figure 3, and is extended around the sprockets 41 and 42 and has its ends fastened to ears or the like 44, projecting from the carriage 29. (Fig. 1.)

Supported on the carriage 29 for lateral sliding movement in a horizontal plane is what I shall for convenience call a column base 47. The outline of the column base 47 95 is shown in Figure 1 and is generally that of an H.

In the upper surface of the carriage 29 and the lower surface of the column base 47 are registering, transversely, extending grooves 100 48 and 49, as shown in Figure 6, in which travel the balls 50 held in the ball containers 51 similar to the ball containers 32 already described.

On the column base 47 is supported the 105 column 52, which may have the reinforcing flanges 53 and the bottom member 54, as shown in Figures 1 and 3.

For moving the column base 47 laterally in the machine, the following means are provided:

Brackets 55 and 56 project upwardly from the carriage 29 at the right-hand side thereof and support a shaft or rod 57 having on its forward end a hand-wheel 58 provided with 110 a handle 59, so located as to be readily and conveniently accessible to the operator of the machine.

At the rear of the machine, there is provided on the carriage 29 a bracket 60. 120 (See Figure 1.) On the shaft 57 is a sprocket 61 aligned with a sprocket 62 on the stub shaft 63 supported by the bracket 60. A chain 64 extends around the sprockets 61 and 62 and has its ends fastened to 125 the column base 47 in any convenient way.

In the particular form of the device here illustrated, I have shown the column 52, which is, of course, fixed on the column base 47 provided with the spaced ears 65. The 130

ends of the chain 64 are connected with threaded bolts 66, which are extended through the ears 65 and are adjustable therein by means of nuts 67 for thus varying the tension on the chain.

By operating the hand wheel 58, the column base 47 and the column 52 supported thereon may be moved laterally in the machine, as may be desired.

- 10 It will thus be seen that the cutters or other operative mechanism mounted on the column 52 may be adjusted to a great variety of positions by means of the horizontal adjustments of the carriage 29 and column base 47 with relation to the frame 10 and with relation to each other.
- 15 I have provided simple means for locking the carriage 29 in any of its adjusted positions and also means for locking the base 47 in its different adjusted positions.

20 For locking the carriage 29 against fore-and-aft sliding movement on the frame 10, there is mounted in the frame 10 a rod or the like 68 on which is a handle wheel 69 (see Figures 2 and 7).

25 It will be understood that the rod 68 has a screw-threaded mounting in the frame 10. The rod 68 extends through an elongated slot 70 in the stop plate 35 hereinbefore referred to and has on its inner end a head 71 bearing against the plate 35.

30 It thus follows that by tightening the head 71 against the plate 35, that plate, which is somewhat resilient, may be drawn into tight engagement with the frame 10 at the edge of the opening 34 for locking the carriage 29 to the frame 10.

35 Before describing the means for locking the column base 47 to the carriage 29, I will describe the means for automatically latching or locking the carriage 29 in its central position of movement.

40 Mounted in a suitable boss 72 on the frame 10 is a rod 73 having thereon a collar 74 (see Figure 3). The upper end of the rod 73 is adapted to enter the small hole 75 in the under surface of the carriage 29 when the carriage is in its central position. A spring 76 yieldingly forces the rod 73 toward the carriage 29.

45 For withdrawing the rod 73 from the hole 75, when it is desired to move the table, there is connected with the rod 73 an arm or the like 77 extending downwardly and pivoted at its lower end to a treadle or the like 78.

50 It will be seen that there is provided the spring-pressed rod 73, which will automatically lock the carriage 29 against further movement whenever the carriage is moved to its central position, and that there is also provided, the locking rod 68 by which the carriage 29 may be locked in other positions of its adjustment.

55 For locking the column base 47 in the various positions of its adjustment on the carriage 29, a screw bolt 79, shown in Figures 1 and 2, is adjustably screwed into the column base 47 and is rotatably extended through a horizontally, elongated slot 80 in a plate 81 secured to one edge of the carriage 29 and extending upwardly therefrom.

60 The bolt 79 has a head 82 so arranged that by screwing the bolt into the column base 47, the plate 81 may be gripped between the head 82 and the column base 47 for locking the column base 47 to the carriage 29.

65 A bearing yoke 83 is provided with ways 84 to receive the column 52 for providing a vertically, sliding adjustment of the yoke 83 on the column 52.

70 For effecting and controlling this adjustment, there is rotatably but non-slidably mounted on the column 52, the rod 85 having at its upper end the hand wheel 86.

75 The yoke 83 has a screw-threaded lug 87 in which a screw-threaded portion of the rod 85 is received.

80 By operating the rod 85, the yoke 83 may be vertically adjusted on the column 52 as may be desired.

85 The yoke 83 supports the split bearings 88 in which is mounted the upper beam or shaft 89. The halves of the bearings 88 may be drawn together for clamping and locking the shaft or beam 89 in any position of its rotatable and longitudinal adjustment by means of the screw bolts 90 and the handles 91 thereon.

90 On the shaft or beam 89 are collars 92 and 93 slidably but non-rotatably supported on the shaft.

95 A pin 95 projects from the yoke 83. A second pin 96 projects from the collar 93 in such manner that the two pins serve as stops.

100 The collar 93 is keyed slidably but non-rotatably on the shaft 89, so that the pins will engage when the motor hereinafter mentioned, which is carried by the shaft 89, stands in position with its shaft vertical.

105 On one end of the shaft 89 is a head 97, having mounted thereon by means of gibbed ways for adjustment radially of the beam or shaft 89, the turret base 98.

110 On the head 97 is a bracket 99 in which is rotatably but non-slidably mounted a shaft or rod 100 on the upper end of which is a hand wheel 101.

115 The shaft or rod 100 has a screw-threaded portion having a screw-threaded connection with the turret base 98, as shown in Figure 2.

120 By adjusting the hand wheel 101, the turret base 98 may be adjusted radially with relation to the beam or shaft 89.

125 There is supported on the turret base 98, a turret 102, which supports the motor 103 for

permitting the motor to be rotated with relation to the shaft or beam 89, so as to present either end of the motor to the work.

The turret 102 has at one end a cylindrical portion 104 from which projects a portion 105, shown in Figure 11, having the shape of a truncated cone tapered toward the cylindrical portion 104.

In the face of the turret base 98 is a slot 10 or groove 106, shown for instance in Figures 8 and 11, the edges of which are undercut, as indicated at 107 in Figure 11.

The lower part of the groove 106 is semi-circular as indicated at A in Figure 8 to receive the portion 105 of the turret, while the side walls are extended upwardly parallel with each other as shown in Figure 8.

Received in the groove 106 of the turret base 98 above the portion 105 of the turret is a block 109, the side edges of which are beveled to fit the walls of the groove 106 and the upper edge of which, assuming the parts to be in the position shown in Figure 8, is flat and horizontal.

It will be seen that the portion 105 can be rotated in its bearing thus formed for rotating the turret and the motor 103 supported on the turret in the manner hereinabove mentioned.

The turret base 98 has in its sides opposite aligned slots 110 and 111 communicating with the groove 106, as shown in Figure 8. The upper walls of the slots 110 and 111 are correspondingly beveled as indicated at 112 in Figure 8. A wedge bar 113 is extended through the slots 110 and 111 just above the block 109 and is provided with two beveled faces 114 to coact with the beveled walls 112.

One end of the wedge bar 113 has the reduced screw-threaded spindle 115 on which is mounted a nut 116 provided with a hand wheel 117.

The parts just described are so arranged and mounted that by drawing the wedge bar shown in Figure 8 toward the left, the beveled faces 114 will coact with the beveled walls 112 to force the wedge bar downwardly against the block 109 for causing the block 109, the lower edge of which fits the portion 105, to be clamped against the portion 105 for locking the turret in the turret base.

The motor 103 is so constructed as hereinabove somewhat more fully referred to that cutters may be mounted upon either end of its shaft, and it is therefore desirable that the motor should be reversible on the turret base by turning it half a revolution, so as to present the cutter on either end of the shaft to the work.

Ordinarily therefore, the motor and consequently the turret are adjusted to two positions only on the turret base.

For quickly and accurately fixing these two positions before adjusting the wedge bar 113 for locking the parts together, there is provided a projecting lug or arm 118, which projects over the cylindrical portion 104 of the turret 102. Slidably mounted in the arm 118 is a tapered pin 119 having the disc-shaped handle or the like 120 and adapted to be selectively driven into either of the tapered holes 121 formed diametrically opposite each other in the surface of the cylindrical portion 104 of the turret 102.

Means might be provided for locking the pins 119 in their inner positions, but I find that by driving them into the tapered holes, they will hold tightly enough for all practical purposes.

The motor 103 is provided with four feet 122, which are formed with elongated slots 123. These feet rest against the face of the turret 102 and adjacent to ribs 124 thereon. (Fig. 10.)

The feet 122 are fastened to the turret 102 by means of cap screws or bolts 125.

It will, of course, be understood that the feet 122 are connected with the motor by means of the legs 126.

In order to provide for final and minute adjustment of the motor longitudinally of its shaft axis on the turret, the following means are provided:

Slidably received between the opposite pairs of legs 126, as shown for instance in Figures 10 and 11, is a wedge, comprising a base 127, a pair of ears 128 projecting toward the motor on one side, and a rib 129 projecting toward the turret 102 on the other side. This rib is inclined at an angle to the longitudinal axis of the base 127 and is received in a similarly inclined slot 130 in the face of the turret 102.

By adjusting the wedge longitudinally when the parts are in the position shown in Figure 10, it will be seen that the wedge will be forced also upwardly or downwardly, because of the travel of the portion 129 in the groove 130, for thus forcing the legs of the motor up or down.

When the proper adjustment of the motor has been reached, the cap screws 125 are tightened.

For conveniently adjusting the wedge 127 and also for swinging the motor in its rotary movement, around a horizontal axis, there is slidably mounted in the ears 128, a rod 131 having at its ends the heads 132.

The rod 131 can be grasped for sliding it quickly in either direction and using one head to tap on the wedge 127 for adjusting that wedge.

The rod 131 can also be used to swing the motor around.

Between the rod 131 and the base 127 of the wedge and between the ears 128 is a

curved, flat spring 133 designed to frictionally engage the rod 131 and prevent accidental sliding movement thereof.

The handle, of course, can be slid so that 5 regardless of which end of the motor is down, the handle may be in position to be actuated by the operator of the machine.

The motor 103 is of standard construction for high speed operations with some 10 slight changes, the important one of which is the projection of the shaft 134 through both end plates of the motor.

Thus the motor can be quickly turned over for presenting the cutter on either end 15 to the work for making cuts of different kinds or for cutting different pieces of wood with the grain differently arranged.

I have provided a mounting in each end 20 of the shaft 134. Cutters of different kinds, as for instance right and left-hand cutters may be mounted in either end of the shaft 134. For this purpose, each shaft end 134 is provided with a tapered opening 135, at 25 the inner end of which is a screw-threaded portion 136, and inwardly therefrom is a smaller screw-threaded portion 137.

I have provided right-hand cutters 138 and left-hand cutters 139, each having a 30 tapered shank 140 to fit in the tapered opening 135.

The right-hand cutters have right-hand screw-threaded spindles 142 to screw into the portion 136 and the left-hand cutters have left-hand screw-threaded portions 141 35 to screw into the screw-threaded portions 137.

I will now explain the various adjustments and operations of my improved universal 40 carving machine and thereafter will explain the operations as applied to a piece of work and in the latter connection will describe certain jigs and other means for mounting the work on the table.

The table 16, as seen in Figure 2, may be 45 adjusted slightly toward the right or toward the left by loosening the set screws 15 of the collars 13 and 14 and adjusting the shaft 12 longitudinally.

Assuming that the table 16 is in horizontal 50 position, it may be adjusted vertically, that is to say radially with relation to the shaft 12 by rotating the hand wheel 24. This rotates the shaft or rod 21 and since the shaft is fixed against sliding movement with relation to the table 16 and has a screw-threaded connection with the ear 19 of the head 17, the rotation of the shaft causes the table 16 55 to slide up and down.

Assuming that it is desired to swing the 60 table around the center of the line of the shaft 12 as an axis, the operator presses on the foot pedal 28^c, causing the upper end of the lever 28^d to engage and force outward one end of the catch 28^b, and causing the 65 other end of the catch 28^b to swing clear of

the head 17 against the tension of the spring 28^c. (See Figures 2, 3 and 5.)

The table is handled during this operation by means of the handle 25, which tends to bring it back until it is stopped in its normal position by the set screw 26 shown in Figure 3.

It will, of course, be understood that before the table is rotated, the hand wheel 12^b, shown in Figures 2 and 4, has been operated to render the clamping blocks 12^a inoperative to hold the shaft 12 against rotation.

Referring now to the various movements and adjustments of the cutters, I will start with the motor and work from it to the 80 frame 10.

It will be noted in the first place that the motor may be adjusted lengthwise of the axis of its shaft by loosening the cap screws 125 shown in Figures 2 and 10 by which the 85 motor feet are connected with the turret 102.

Thereupon, the rod 131 may be used for moving the wedge 127 endwise for securing the proper adjustment of the motor for centering it so that it may be reversed and yet bring each of the two cutters into interchangeable positions.

When this adjustment has been reached, the cap screws 125 are tightened, and ordinarily this adjustment is not changed during the operation of the machine.

The motor can then be reversed in position by giving it a half turn to present either end of its shaft toward the table and the work 100 thereon, in the following manner:

The operator grasps the head 120 of the tapered pin 119 to withdraw the pin from the hole 121 (see Figure 9), whereupon the handle 131 may be grasped for swinging the 105 motor over.

When the motor has been turned over, the tapered pin 119 is pushed into the opposite hole 121 from that which it originally occupied.

Similarly, when it is desired to swing the motor around the axis of the shaft 89 for bringing the cutter on the motor shaft into operative relation with a certain piece of work on the table 16, the operator grasps 115 the handles 91 to loosen the screws 90 so as to permit the shaft 89 to rotate readily in the bearings 88.

If it is desired to adjust the motor toward or from the table 16 from its position shown 120 in Figure 2 for changing the radius at which the cutter on the motor will swing, the operator rotates the hand wheel 101 for raising or lowering the turret base 98 with relation to the head 97. (See Figure 2.)

A vertical adjustment of the shaft 89 is provided and by rotating the wheel 86, the yoke 83 may be raised or lowered on the column 52. (See Figures 2 and 3.)

If it is desired to move the motor from 130

its central position shown for instance in Figure 2 forwardly or rearwardly on the operator's side of the machine, the hand wheel or head 69 is actuated for releasing the grip of the head 71 against the plate 35 and the grip of the plate 35 against the carriage 10, and thereupon the hand wheel 39 can be rotated for imparting rotation to the shaft 36 and actuating the chain 43 shown in Figures 2 and 3.

The chain 43 travels around the sprockets 41 and 42 and being secured to the ears 44 on the carriage 29, as shown for example in Figure 1, will roll the carriage 29 forwardly and rearwardly carrying with it the column base 47, the column 52 and the parts supported thereby.

If it is desired to move the column base 47 laterally toward or from the table 16, the operator rotates the head or hand wheel 82 (shown in Figures 1 and 2) for releasing the frictional grip between the plate 81 and the column base 47, and then rotates the hand wheel 58 for actuating the shaft 59, sprockets 61 and 62 and the chain 64.

The chain 64 being secured to the column 53 and thus to the column base 47 moves the base and the parts carried thereby laterally.

When the adjustment has been made, the head 82 is screwed tight and the parts are thus locked.

It will thus be seen that I have provided a carving machine having mechanical structure whereby a right or left hand cutter 35 may be made to operate upon stock placed on the table, and whereby cutters placed on either end of the motor shaft may be easily moved to operative position.

I have provided further such a structure as will permit the cutter, which is in use, to travel in a straight horizontal line forward or back from the operator or in a straight, horizontal line to the right or to the left.

By the adjustment either of the carriage 29 or the column base 47 by the mechanism provided therefor during the operation of the cutters, the cutters may be made to travel in any direction in a horizontal plane.

Likewise the operator may swing the cutters and at the same time move the column 52 toward or from him or laterally by the means herein described, while the cutter is being swung on the arc of a circle, giving to the cutter in addition to its swinging movement, a forward and back motion or a right and left motion or any combination of these movements.

In addition to the above movements, the table with the work or stock mounted thereon may be moved in the arc of a circle past the cutter in a vertical plane swinging toward and from the operator.

There is thus provided a mechanism capable of a great variety of movements, where-

by almost any type of machine carving can be carried on.

This not only makes it possible to produce a vast variety of finished shapes, but also makes possible the quick and easy adjustment of the machine to take into consideration the direction of the grain of the wood being operated upon.

In Figure 14, I have shown a completed piece of work comprising a volute 143 used on top of a newel post, having the inclined portion or easing 144 to be connected with the lower end of a stair rail.

The volute may be made from a single piece or it may be assumed that the wood from which this piece of work is to be formed has been glued together for instance in two pieces B and C, as shown in Figure 15, and that the side curves and the curve of the easing from the horizontal have been made by sawing the sides and top and bottom of a piece of work on a band saw or the like, then carving for giving the finished shape to the piece may be quickly and easily accomplished with my machine.

I provide for holding the work on the table 16 suitable jigs.

In Figures 18 and 19, I have shown one of these jigs 145 gripped to the table by means of clamp plates 146 and cap screws 147. The particular jig now under consideration is intended to fit the under surface of the irregular volute-shaped carving shown in Figure 14.

For clamping the work to the jigs, any suitable clamping devices may be provided.

I have shown the piece of work D placed upside down on the jig 145 in Figure 18. The jig is provided at one end with an upwardly projecting lug 148 through which is extended a set screw 149 to engage the upper end of the easing 144, which is not spoiled if it is slightly marred. On the set screw 149 is a suitable adjusting handle 150. As many of the set screws may be employed, as is desired.

For engaging the opposite side of the work, I provide a peculiar clamping or gripping member, such as is shown in Figures 18, 19 and 20. This member comprises a jaw 151 having an elongated slot 152 therein. A bolt 153 is mounted in the jig 145 and is clamped by means of a nut 154, which draws the shoulder formed by the cylindrical portion 155 of the bolt against the jig.

The bolt has a squared end 156 received in the side portion 157 of the upper side of the slot 152. The head or end 156 holds the body 151 snugly against the jig 145, but permits sliding movement of the body 151.

At one end of the body 151 is a toothed portion or the like 158 for engaging the work.

Connected with the bolt 153 and extending at right angles therefrom through the hole 159

159 in the body 151 is a rod or the like 160 forming an extension on the bolt and screw-threaded at its outer end, as at 161, to receive a nut 162.

5 By rotating the nut 162, the tooth 158 of the clamp body 151 may be caused to grip the work as illustrated in Figure 18.

As many of these clamp devices may be used as are necessary to hold the work, and 10 the number is determined by the character of the work and by the jig.

Assuming that the piece of work D is mounted on the table on the jig, as shown in Figure 18, a pattern 163 is placed on 15 the upper side of the work, which in the particular instance now under consideration, is the bottom of the piece, for guiding the operator in finishing the carving operation.

The pattern is held in place by means of 20 a hook bolt 164, the hook 165 of which is engaged over the pattern and the shank of which extends through the jig 145 and is locked in place by means of a nut 166.

The pattern may be fastened to the work 25 by means of screws 167 also if desired.

It will, of course, be understood that any suitable means for mounting the work on the table may be employed.

For purposes of illustration, I will assume 30 that the table is in horizontal position and that the operator desires first to cut or carve the sides of that portion of the work which lies in horizontal position. This happens to be in the present instance the main body 35 of the volute 142 carved as shown in a horizontal plane. The table is locked in horizontal position.

The motor is adjusted until the cutter on the motor shaft is adjacent to the work at 40 the point where the carving operation is to begin.

In order to facilitate the following of the pattern, a guide cylinder or sleeve 168 is mounted on the motor shaft bearing adjacent to the cutter. The diameter of the guide sleeve 168 may be varied by placing shells thereon. The sleeves 168 are attached to the end plate 169 of the motor and do not rotate with the shaft.

50 The cutter having been adjusted until it stands approximately at the point e (see Figure 15), the motor is adjusted, the carriage and the base are released from their locking means, and the operator operates the two 55 hand wheels 58 and 38 for causing the cutters to follow the pattern in the direction indicated by the arrow 170 in Figure 15.

It will be understood that a right or left-hand cutter is employed depending upon 60 the direction of the grain of the wood along the line to be cut.

The cutter f illustrated diagrammatically in Figure 15 rotates in the direction indicated by the arrow thereon.

65 This operation is continued until the cutter

reaches the point g in Figure 15. Then the cutter is moved away from the work, carried around to the point h to clear that portion between g and h where the grain can not be properly cut by the cutter and 70 would be likely chipped or split.

The cutter is started to work again at the point h and the machine similarly operated until the point i is reached.

In order to properly work with the grain, 75 the cutter is then moved to the point j and the side of the work from the point j to the point k is cut.

The cutter is then again swung away from the work and moved to the point l and the 80 side of the work is carved from the point l to the point m.

The operator then turns the motor over in the manner hereinbefore described and carves the work from the point g to the point 85 h and then from the point i to the point j and from the point k to the point l.

Ordinarily the cutter, as illustrated in Figure 16, carves only a portion of the thickness of the side of the work leaving the lower 90 portion to be subsequently finished.

The cutter is then adjusted to position for instance adjacent to the point e and the table is released from its locking device and is swung by the handle 25, while at the same 95 time, the hand wheel 58 would be actuated for causing the cutter to follow the pattern, until the carving is completed from the point e to the point n.

The cutter is then adjusted to the point 100 n and a similar operation is performed to complete the carving from the point n to the point o.

During these latter two cuts, the carriage 29 is locked in its central position 105 by the pin 76.

After completing this operation on a number of parts, the cutter is moved out of the way and the pattern and work removed from the jig and the attachment 110 bracket 171 is mounted on the jig.

The partly finished volute is then turned over with the upper end of the bracket 171 supporting the upper end of the easing. Clamps 172 similar to the clamps 151 may 115 now be substituted for the clamps 151. The forms of the clamps 172 are simply suggested and are here used because the portions 173 which engage the work are of such shape as to fit the molding or rib or other shape 120 given to that portion of the work, which has been curved.

A cutter 138^a is then mounted on the motor shaft for finishing the carving of the upper portion of the side of the work. This 125 cutter is provided with a lower non-cutting portion 174, which serves as the guide and makes it unnecessary in the particular piece of work now being illustrated to use a pattern on the top of the work.

It will be noted that in the particular work now being illustrated, a rib 175 is left on top of the work and this may be taken off subsequently by hand.

5. It will be noted from the foregoing that work can be carved for making irregular or curving surfaces of almost any desired shape.

By properly mounting the work and 10 swinging either the table or the cutter around their respective axes of rotation, a piece of work can be carved for cutting on almost any desired curve in a vertical plane.

By operating the hand wheels 38 and 58, 15 the cutter may be actuated for carving the work for any curve in a horizontal plane.

By swinging the table around its axis of rotation and operating either one or the other of the hand wheels 38 or 58, the work 20 can be carved on curves in horizontal and vertical planes and combinations thereof.

The machine can be readily adjusted or the cutters changed to accommodate the machine to the grain of the wood.

25. The machine particularly effects tremendous saving on work that heretofore has been performed entirely or largely by hand.

It will be noted that while I have described and claimed the table and cutter as 30 in certain assumed normal positions and have for instance referred to the horizontal adjustment of the table, I do not desire to limit myself to a structure as described here for purposes of illustration. For example, if the machine shown in the drawings were turned a quarter turn to the right, 35 it would still embody the principles of my invention, and yet what I have called in the present specification, horizontal adjustment of the cutter would then include both vertical and horizontal adjustment of the table.

Changes may be made in the details of the structure and arrangement of the parts of the machine without departing from the 40 real spirit and purpose of the invention, and it is my object to cover by my claims, any modified forms of structure or use of mechanical equivalents, which may be reasonably included within their scope.

50. I claim as my invention:

1. In a carving machine, a frame, a work table mounted thereon, a cutter, means for mounting said cutter for swinging it about an axis, and means for adjusting said cutter radially of such axis, said device including means for supporting said cutter for independent fixed rotary adjustment with relation to its axis of rotation, said device having means for affording fixed radial adjustment of the cutter with relation to the axis of its first-mentioned rotary swinging movement.

60. 2. In a carving machine, a frame, a work table mounted thereon, a cutter, means for mounting said cutter for swinging it about

an axis, and means for adjusting said cutter radially of such axis, said device including means for supporting said cutter for independent fixed rotary adjustment with relation to its axis of rotation, said device 70 having means for affording fixed radial adjustment of the cutter with relation to the axis of its first-mentioned rotary swinging movement, said device having additional means for adjusting the cutter toward or 75 from the table.

3. In a carving machine, a frame, a work table mounted thereon, a cutter, means for mounting said cutter for swinging it about an axis, and means for adjusting said cutter 80 radially of such axis, said device including means for supporting said cutter for independent fixed rotary adjustment with relation to its axis of rotation, said device 85 having means for affording fixed radial adjustment of the cutter with relation to the axis of its first-mentioned rotary swinging movement, said device having additional means for adjusting the cutter toward or 90 from the table, and means for adjusting the table toward or from the cutter.

4. In a carving machine, a frame, a work table mounted thereon, a cutter, means for mounting said cutter for swinging it about an axis, and means for adjusting said cutter 95 radially of such axis, said device including means for supporting said cutter for independent fixed rotary adjustment with relation to its axis of radial adjustment of the cutter with relation to the axis of its first-mentioned rotary swinging movement, said device having additional means for adjusting the cutter toward or from the table, and means for adjusting the table toward or 100 from the cutter, said device having also means for rotating the table around an axis 105 during the operation of the cutter.

5. In a carving machine, a work support table and a cutter, means for mounting said table and cutter for swinging movement 110 around and at different distances from spaced horizontal axes and means for locking each whereby the work placed on said table may be cut on a radius, the curve thereby produced on the work bending up or down depending on whether the table or cutter is swung on its axis.

6. In a carving machine, a work support table and a cutter, means for mounting said table and cutter for swinging movement 115 around spaced horizontal axes and means for locking each whereby the work placed on said table may be cut on a radius, the curve thereby produced on the work bending up or down depending on whether the table or cutter is swung on its axis, and means for affording radial adjustment of the cutter 120 and the table with relation to its axis of rotation.

7. In a carving machine, a frame, a table 130

supported thereon, a motor having a shaft adapted to carry cutters on either end, means for mounting said motor on said table for presenting either end of its shaft to the work on the table and means for adjusting said motor on said table longitudinally relative to the shaft of the motor for positioning said cutters to assume the same position when the mounting means is operated to present the respective cutters to said work.

8. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head on the shaft, a turret base mounted on the head for radial adjustment with relation to the shaft, and a motor supported on said turret base.

25 9. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head 30 on the shaft, a turret base mounted on the head for radial adjustment with relation to the shaft, and a motor supported on said turret base for rotatable adjustment for presenting either end of its shaft to work on the table.

10. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head 45 on the shaft, a turret base mounted on the head for radial adjustment with relation to the shaft, and a motor supported on said turret base for rotatable adjustment for presenting either end of its shaft to work on the table, said device having additional means for affording adjustment of the motor lengthwise of the axis of its shaft.

60 11. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft,

means for mounting the shaft for permitting it to rotate on the column, said means being vertically adjustable on the column, a head on the shaft, a turret base mounted on the head for radial adjustment with relation to the shaft, and a motor supported on said turret base, said table being mounted for rotary adjustment.

12. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head on the shaft, a turret base mounted on the head for radial adjustment with relation to the shaft, and a motor supported on said turret base, said table being mounted for rotary adjustment and for radial adjustment with relation to its axis of rotation.

25 13. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head on the shaft, a turret base mounted on the head for radial adjustment with relation to the shaft, and a motor supported on said turret base for rotatable adjustment for presenting either end of its shaft to work on the table, said table being mounted for rotary swinging movement.

14. In a carving machine, a frame, a table supported thereon, a carriage, means for adjusting said carriage horizontally on said table, a column base, means for adjusting said column base horizontally on said carriage at right angles to the carriage adjustment, a column on said column base, a shaft, means for mounting the shaft for permitting it to rotate on the column, said means being vertically adjustable on the column, a head on the shaft, a turret base mounted on the head for radial adjustment with relation to the shaft, and a motor supported on said turret base for rotatable adjustment for presenting either end of its shaft to work on the table, said table being mounted for rotary swinging movement and for radial adjustment with relation to the axis of its rotary movement.

15. A machine of the class described comprising a work table and a cutter supported to carve work on the table, the support for said cutter being rotatable, means for ad-

justing the cutter relative to its support whereby it may be swung at various radii, said cutter being rotatably mounted relative to its support for rotation independent of the rotation of the support, means for locking such rotation comprising a cylindrical portion, a half circle socket engaging one-half of said cylindrical portion and a slidably mounted block for engaging the other half thereof and means for sliding said block to cause it to frictionally engage the cylindrical portion.

16. A cutter supporting mechanism comprising a rotatably mounted shaft, a head 15 adjustable across the end thereof, a motor supported on said head for slidable movement thereon longitudinally of the shaft of the motor and means for causing such sliding movement comprising an angularly disposed slot in said head, a slidably mounted block in the base of said motor and an angularly disposed projection on said block adapted to fit in said slot.

17. A cutter supporting mechanism comprising a rotatably mounted shaft, a head 25

adjustable across the end thereof, a motor support rotatably mounted on said head, a motor supported on said motor support for slidable movement thereon longitudinally of the shaft of the motor and means for causing such sliding movement comprising an angularly disposed slot in said head, a slidably mounted block in the base of said motor and an angularly disposed projection on said block adapted to fit in said slot. 30

18. In a carving machine, a frame, a work table mounted thereon, a cutter, means for mounting said cutter for swinging it about an axis transversely to its own axis, means for adjusting said cutter radially of such axis and means for moving said cutter along its own axis and relative to said last means, said means for so moving the cutter comprising a slidably mounted block having an angularly arranged projection and a groove 40 45 in the means for mounting said cutter, said projection being adapted to slide in said groove.

Des Moines, Iowa, October 7, 1925.
SERN MADSEN.
